CLAIM

The ornamental design for an adapter base for fluorescent lamp, as shown and described.

DESCRIPTION

FIG. 1 is an isometric view of the adapter base for fluorescent lamp showing my new design;

FIG. 2 is a right side elevational view thereof;

FIG. 3 is a top plan view thereof;

FIG. 4 is a bottom plan view thereof;

FIG. 5 is an isometric view of a second embodiment of my new design;

FIG. 6 is a side elevational view thereof;

FIG. 7 is a top plan view thereof;

FIG. 8 is a bottom plan view thereof;

FIG. 9 is an exploded isometric view of the first embodiment of the design, the fluorescent lamp being fragmentarily shown in broken lines for illustrative purposes only;

FIG. 10 is an exploded isometric view of the second embodiment of the design, the fluorescent lamp being fragmentarily shown in broken lines for illustrative purposes only.

FIG. 1

FIG. 2

FIG. 3

FIG. 4

FIG. 5

FIG. 6

FIG. 7

FIG. 8
